UNITED STATES PATENT OFFICE.

JOHN STEVENS EDDY, OF CHICAGO, ILLINOIS, ASSIGNOR OF ONE-HALF
TO MILTON SMITH, OF DENVER, COLORADO.

SPRING-TIRE.

SPECIFICATION forming part of Letters Patent No. 556,498, dated March 17, 1896.

Application filed July 3, 1895. Serial No. 554,877. (No model.)

To all whom it may concern:

Be it known that I, JOHN STEVENS EDDY, a citizen of the United States, residing at Chicago, in the county of Cook, State of Illinois, 5 have invented a new and useful Improvement in Steel Spring-Tires; and I do hereby declare the following to be a full, clear, and exact description of the invention, such as will enable others skilled in the art to which it app-
10 pertains to make and use the same.

My invention relates to improvements in steel spring-tires for bicycles, buggies and other vehicles, and belongs especially to that class of tires described in my patent, numbered 530,888, dated December 11, 1894. In the patent referred to I have shown and described a single series of flat, circular steel springs placed side by side and held together by two bars or straps, the whole having a
20 rubber covering.

My present invention consists, substantially, of a double series of flat circular steel springs, an outer and an inner series, the outer series being united by two flat steel bars or strips, as in said patent, but the inner series held together and to the outer series by one only of the said flat steel bars that unite the outer series and by an independent or third flat steel bar, the whole forming two
25 30 solid elastic cylinders, one inclosed by the other and having a covering or outer tire, all as more fully hereinafter described and particularly claimed.

The objects of this improvement are to reinforce the outer spring-cylinder, to increase the resiliency of the tire, and to render it more durable.

My invention is illustrated in the accompanying drawings, in which—
40 Figure 1 is a perspective view of one of the outer and one of the inner circular spring-rings, showing the same fastened to the bars; Fig. 2, a sectional view of tire; Fig. 3, a side view, and Fig. 4 a sectional view, of modification.

45 Referring to the drawings, *a* are the outer flat circular steel springs made in the form of rings. These rings are preferably made so that their width gradually narrows as they
50 approach the part intended to be placed near-

est to the rim and hub of the wheel, are each formed from a single piece of steel, and are either lapped or brazed at the ends.

b are flat circular steel springs similar to rings *a*, but of less diameter than the latter, and are adapted to be encircled by the rings *a*.

c and *d* are two flat bars, each made from a single piece of metal, one end of each of the said bars being provided with a shoulder *e*, 60 so that the ends when brought together may be easily united and present a continuous smooth surface. The ends of these bars or strips *c* and *d* may be united in any suitable manner, a convenient method being by the 65 employment of a screw *f*, as shown in the drawings.

The flat circular spring-rings *a* are placed edge to edge and in this manner a closed circular cylindrical figure is formed, each spring- 70 ring being separately riveted or otherwise secured to the bars *c* and *d*. The inner series of spring-rings *b* are arranged in a similar manner and are fastened below to the bar *d*, by which means the outer and inner series of 75 rings are united at one point, but above the inner series are united to an independent bar *g*, which bar is similar in form and structure to bars *c* and *d*.

The word "above" is used to designate the 80 part of the circular springs farthest from the rim and hub of the wheel, and the word "below" to designate the part of the circular spring nearest.

I sometimes prefer to make the inner spring- 85 rings, *b*, and the outer rings, *a*, of one piece of metal, as is illustrated in Fig. 4—that is to say, of a single piece of steel the length of which is a little greater than the circumference of both rings. This is bent so as to form 90 both the inner and outer rings, the ends being rigidly fastened to the flat bar *d* in the same manner as when the two rings are made of separate pieces of metal.

L is a rubber covering surrounding the 95 outer series of spring-rings and covering the whole.

It will be noticed by the construction of a tire as herein described a simple tire is provided, one that will constitute a perfect cy- 100

cylindrical spring having a rubber covering surrounding it. This tire may be easily applied to a bicycle or vehicle wheel.

Having thus described my invention, what 5 I claim is—

1. An elastic tire composed in combination of an outer and inner elastic cylinder, each of said cylinders composed of flat metal spring-rings, means for connecting the cylinders at one point, and means for uniting and holding said rings in close contact, substantially as described.

2. A tire for bicycles and other vehicles, consisting of an outer series of independent, flat, 15 circular, metal spring-rings, arranged in contact, bars, *c* and *d*, uniting said rings, an inner series of independent, flat, circular metal spring-rings, arranged in contact, said inner series fastened below to bar, *d*, and above to

bar, *g*, each of said rings independently secured to said bars, the whole having a rubber covering, substantially as described.

3. A tire for bicycles and other vehicles, consisting of an outer series of metal spring-rings arranged in contact, and an inner series of 25 metal spring-rings arranged in contact, a single piece of metal forming an outer and an inner ring of said series, the connecting-bars for uniting and holding said rings, the whole having an outside covering, substantially as 30 described.

In testimony whereof I affix my signature in the presence of two witnesses.

JOHN STEVENS EDDY.
